UNITED STATES PATENT OFFICE.

WILLIAM F. FOLMER, OF ROCHESTER, NEW YORK, ASSIGNOR TO EASTMAN KODAK COMPANY, OF ROCHESTER, NEW YORK, A CORPORATION OF NEW YORK.

APPARATUS FOR MAKING IDENTIFYING-PHOTOGRAPHS.

1,324,887.

Specification of Letters Patent.

Patented Dec. 16, 1919.

Application filed September 20, 1918. Serial No. 254,925.

To all whom it may concern:

Be it known that I, WILLIAM F. FOLMER, a citizen of the United States, residing at Rochester, in the county of Monroe and State of New York, have invented certain new and useful Improvements in Apparatus for Making Identifying-Photographs; and I do hereby declare the following to be a full, clear, and exact description of the invention, such as will enable others skilled in the art to which it appertains to make and use the same.

My invention relates to photographic apparatus and has for its object to provide a device by means of which photographs may be readily and quickly made of persons, together with such personal data as may be necessary for their complete identification, which photographs may be printed upon or applied to cards, pass-ports, passes or other documents, and the identity of the holder may be determined beyond question. At the present time these identification cards are used in large quantities in order to prevent unauthorized persons from entering factories where munitions are produced, and as the personnel of the working force changes almost from day to day, it is essential that such cards be capable of production with rapidity and certainty. To these and other ends the invention resides in certain improvements and combinations of parts, all as will be hereinafter described, the novel features being pointed out in the claims at the end of the specification.

In the drawings:

Figure 1 is a side elevation of an apparatus embodying my improvement.

Fig. 2 is a plan view of the same, the upper portion of the casing for the illuminating devices and of the standards being shown in sections.

Fig. 3 is an end elevation looking from the lefthand side of Fig. 1,

Fig. 4 is a vertical sectional view taken on the line $x-x$ of Fig. 1,

Fig. 5 is a vertical sectional view on the line $y-y$ of Fig. 2, and

Fig. 6 is a view of the photograph made by use of the apparatus.

Similar reference numerals in the several views indicate the same parts.

The apparatus as a whole embodies certain measuring and indicating devices and all or a portion of a photographic outfit

mounted upon a support which is readily manipulated by a single operation. The supporting frame of the device consists of a base portion 1 resting upon the floor, having standards 2 provided with ways at their inner sides in which is guided a frame supporting the camera, the measuring devices and suitable lighting appliances. Attached to the front of the base or stationary support is a frame embodying a horizontal member 3 and an inclined bracing member 4, to the front end of which latter is attached a vertical member 5, bearing at its inner edge a scale 6 containing indications marked off in feet and inches. As this scale is to indicate the height of the person photographed, it is only necessary that it should contain the indications in inches and half inches from four feet six inches up to six feet six inches (4' 6" up to 6' 6"), although, if desired, it may contain other designations. The face of this scale is at approximately the correct focal distance from the film or plate in the camera to be used, so that the designations and the height indicator will appear sharply in the photograph to be taken. Mounted upon the standards 2 and vertically adjustable thereon is a table or support embodying the horizontal members 7 connected by the cross members 7^a and the vertical members 8 sliding in guides formed in the inner sides of the standard. This frame is adapted to be adjusted vertically by suitable means, such as pinions 9 on a shaft 10 carrying a hand operating wheel 10^a, said pinions meshing with racks 11 attached to one side of the vertical standards 2. The adjustable support or table carries at one end the camera 12 of any suitable construction, but preferably of fixed focus and of a type embodying an oscillatory handle 13, which, when operated, will not only cause the exposure of the film or plate, but will feed a new sensitized surface into position, in order that photographs of the subject may be taken rapidly by comparatively few and simple operations. Located upon the front end of the table or support 7 are the means for illuminating the subject photographed, consisting in the present instance of two chambers 15 and 16, covered at the front with a suitable light diffusing medium, such as ground glass 17, the curved walls of the chambers serving to concentrate the light upon the subject, and for the pur-

pose of causing the image to appear more or less in relief, the opposite sides of the face are illuminated with lights of different intensity, thus, in the present instance, the 5 chamber 15 contains a single electric bulb 15^a, while the chamber 16 contains a plurality of bulbs indicated by 16^a and producing a more intense illumination of the left-hand side of the face of the person being photographed. Extending in the front of the 10 light chambers are wings 18 for the purpose of excluding the extraneous light, connected at the top by a cross piece 20, through which is provided an aperture 21 for the 15 passage of the marking or measuring scale 6 when the camera frame is lowered to its extreme position. 22 indicates a marker or index in the form of a rod extending between the wings 18, preferably having at its 20 center a marker or enlargement 23, said index rod or that portion of it preferably containing the marker 23 being in the field of exposure of the camera and coöperating with the scale 6 to indicate in feet and 25 inches the distance of said index above the floor or support upon which the person being photographed stands. 40 indicates a curtain constituting a background or screen, supported at its upper end upon forwardly 30 extending rods 41 attached to the wings 18. Secured at the front end of the table 7 is a changeable or variable designating device which may be set by the photographer standing in proximity to the camera so as to cause 35 the picture produced, to contain identifying or designating matter relating to the individual being photographed, such as designating letters or numbers, or which may indicate the number or series of the particular 40 pass or identification card appropriated to him. In the present instance this designating means consists of a plurality of series of movable tablets containing designations such as letters or numbers, any of 45 the tablets of each series being movable by the operator into the field of the lens and preferably in proximity to the face of the person being photographed. The tablets indicated by 25, of each series are flexibly 50 connected and are hung from polygonal blocks 27 mounted on a shaft 28, each block having at one side a pulley 29 around which is extended an endless belt 30 passing below a guide rod 31 and around a pulley 32 located in proximity to the camera. In the embodiment shown the first of the series of tablets indicated by 33 contains a designating letter of the alphabet, and the others in the series numerals from naught to nine (0 55 to 9), and by manipulating the cords or cables 30, the camera operator can bring the appropriate tablets into the field of exposure. 45 indicates a cover plate arranged at the front of and preferably extending over the 60 indexing tablets, serving also as a subject po-

sitioning stop adapted to contact with the chest of the person photographed, so that his face will be substantially in the plane of the scale and in the focus of the camera lens.

70

In using the apparatus the operator stands at the lefthand end of the instrument shown in Fig. 1, in convenient position to operate the camera and the adjusting devices, and the person to be photographed stands at the opposite end, with his chest, or a portion of his body, in contact with the positioning stop 45. The operator by means of the hand wheel 9 adjusts the frame bearing the camera until the index rod 22 rests upon the 80 head of the subject, whose height above the floor is thus indicated in feet and inches upon the scale 6. By manipulating the cords or belts 30, the tablets 25 appropriate to the particular subject are brought into the 85 field of the camera and the subject and scales being suitably illuminated by the lamps, the exposure is made by operating the handle 13 of the camera or otherwise.

It will be noted that all the devices for 90 adjusting the parts and making the exposure are located in juxtaposition, so that a single operator can measure, designate and photograph the operatives when entering or leaving a building without delay and in 95 practical use in many factories, the apparatus has been found eminently efficient.

The negative made by the exposure, and consequently the print, will be substantially as shown in Fig. 6, and this picture applied 100 to an identifying pass that would indicate at once the series and number either of the individual or the pass, his height and his facial characteristics.

Instead of mounting the illuminating devices upon the adjustable frame, they could be arranged otherwise, but it is desirable to employ the complete measuring, designating and photographic unit, which may be used in any situation and does not require 110 the services of a skilled operator.

Having described my invention, what I claim and desire to secure by Letters Patent is:

1. A photographic apparatus embodying 115 a stationary support, a vertically adjustable support mounted thereon, a photographic camera on the adjustable support, and indicating means arranged between the supports comprised within the field of the camera lens and coöperating with the subject photographed to indicate the relative 120 adjustments of the supports.

2. A photographic apparatus embodying 125 a stationary support, a vertically adjustable support mounted thereon, a photographic camera on the adjustable support and means arranged between the supports for indicating their relative adjustments comprised within the field of the camera lens.

180

3. A photographic apparatus embodying two relatively adjustable supports, a camera carried by one of them and both supports co-operating with the subject to be photographed, means for indicating the relative adjustments of the supports as determined by a dimension of the subject, said means being comprised within the field of the camera lens.
- 10 4. A photographic apparatus embodying two relatively adjustable supports, a camera carried by one of them and both supports co-operating with the subject to be photographed, means for indicating the relative 15 adjustments of the supports as determined by a dimension of the subject, and changeable designating means having operating devices arranged in proximity to the camera controlling devices, said indicating and 20 designating means being comprised within the field of the camera lens.
5. In a photographic apparatus, the combination with a base carrying a scale, a vertically adjustable support thereon and a 25 camera on the latter, of an indicator carried by said support adapted to coöperate with the upper portion of the subject to be photographed and with the scale on the base, said scale and indicator being within the field of 30 the camera lens.
6. In a photographic apparatus, the combination with a base and a height scale thereon, of a support vertically adjustable on the base, having an indicator coöperating 35 with the scale on the base and with the subject being photographed, a positioning stop for the subject, and a camera on the support, said scale and indicator being located within the field of the camera lens.
- 40 7. In a photographic apparatus, the combination with a base, a support vertically adjustable on the base, means for indicating
- their relative adjustments coöperating with the subject to be photographed, and means for adjusting said support, of a camera on 45 the support having an exposure control, said support adjusting means and exposure control arranged in juxtaposition and said indicating means being located within the field of the camera lens when covering the subject photographed.
8. In a photographic apparatus, the combination with a base, a support vertically adjustable thereon, a camera at one end of the support, a positioning stop at the other 55 end of the support for locating the subject, and means for illuminating the subject mounted on the support, of a changeable designator, an indicator coöperating with the subject and indicating the relative adjustments of the base and support, said designator and indicator being located within the field of the camera lens when the subject is being photographed.
9. In a photographic apparatus, the combination of a support, a camera thereon, a subject positioning stop on the support in front of the camera, and illuminating devices of different intensity located on opposite sides of the lens axis and directing light 70 rays upon the subject when adjacent the positioning stop.
10. In a photographic apparatus, the combination with a base, a vertically adjustable support thereon, of a camera, a subject positioning stop, and a subject illuminating device and an indicator for engaging the top of the head of the subject, all mounted upon and movable with the support, and a scale on the base, with which the indicator coöperates and arranged upon the base within the 75 80 field of the camera lens.

WILLIAM F. FOLMER.
